UNITED STATES PATENT OFFICE.

JACK CALDWELL, OF KANSAS CITY, MISSOURI, ASSIGNOR OF ONE-HALF TO CHARLES HOWARD, OF SAME PLACE.

LIFTING-JACK.

SPECIFICATION forming part of Letters Patent No. 653,283, dated July 10, 1900.

Application filed March 10, 1899. Serial No. 708,584. (No model.)

To all whom it may concern:

Be it known that I, JACK CALDWELL, of Kansas City, Jackson county, Missouri, have invented certain new and useful Improvements in Lifting-Jacks, of which the following is a specification.

My invention relates to lifting-jacks, and more especially to that class wherein an intermeshing worm shaft and wheel are adapted to raise and lower a vertical screw engaging internal threads on the wheel, accordingly as the latter is turned in one direction or the other; and one object is to produce a lifting-jack of this character and of simple, comparatively-cheap, small, and compact construction, with great capacity for lifting.

Other objects will hereinafter appear; and the invention consists in certain novel and peculiar features of construction and combinations of parts, as will be hereinafter described and claimed.

In order that the invention may be fully understood, reference is to be had to the accompanying drawings, in which—

Figure 1 represents a vertical central section of a lifting-jack embodying my invention. Fig. 2 is a view, partly in horizontal section and partly in plan, the cover-plate being omitted. Fig. 3 is an irregular section taken on the line III III of Fig. 4. Fig. 4 is a section taken at right angles to the section shown in Fig. 3. Fig. 5 is a horizontal section taken on the line V V of Fig. 1.

In the said drawings, 1 designates the heavy cast-metal base or stand of the lifting-jack, said base being cast with a handle 2 and with a circular chamber 3 and an offsetting chamber 4, the latter being formed in the rectangular enlargement 5, provided at one end with a journal-opening 6 and at its opposite end with a threaded opening 7, said openings being axially alined. The end wall of said enlargement having the journal-opening is provided with a channel or groove 8 in its inner side, and concentrically surrounding the opening 6 and seated in said channel are the antifriction-balls 9, hereinafter more particularly referred to. The base of the chamber 3, concentrically thereof, is formed with a groove 10; semicircular in cross-section, and seated

therein are antifriction-balls 11 of comparatively-large size.

12 designates a worm-wheel having its periphery channeled out or grooved and having its teeth 13 of segmental form for a purpose 55 which will presently appear. The hub 14 of each wheel has an annular groove 15, within which projects the retaining-screw 16, mounted in the base or stand and adapted to prevent any upward movement of said wheel, 60 the latter being also provided in its under side with a groove 17, engaged by the antifriction-balls 11, hereinbefore referred to. The hub is internally threaded, as at 18, and provided with one or more inclined oil-passages 19 in order that a lubricant, preferably 65 castor-oil, poured in the chamber 3 may pass down through said passage and thoroughly lubricate the vertical screw 20, engaging thread 18 of the worm-wheel. Said screw is 70 provided with an enlargement or head 21, having its upper surface preferably roughened, and below said head with a pair of holes 22, extending at right angles to each other, in order that the lever or rod may be engaged 75 therewith to turn the screw, and therefore raise or lower an object, this method of turning the screw being resorted to only where it is impossible or inconvenient to manipulate the lever or crank, hereinafter referred to. 80

23 designates a shaft journaled near one end in the opening 6 and formed with a worm-thread 24, engaging the peripherally-grooved teeth of wheel 12, the grooved or curved formation of teeth 13 having a long bearing on 85 the thread 24 in order to effect a stronger connection between said parts than if said teeth were straight.

The worm-shaft is provided with a removable collar 26, secured rigidly by a set-screw 90 28 and having a circular groove 27 to receive the antifriction-balls 9, and is also provided with a rigid collar 28^a, having an annular groove 29 to receive the antifriction-balls 30, occupying the groove 32 of the screw-plug 31, 95 engaging the threaded opening 7 and forming a journal for the corresponding end of the worm-shaft. To secure the shaft and bearing-balls in the position described, it is necessary first to arrange the base or stand on its 100

side, so that the bearing-balls 9 will be retained in position when placed in the groove 8. The collar 26 is then placed upon said balls and the shaft slipped down through the opening 7, said collar 26, and the journal-opening 6 until its threaded end engages the threads of the wheel, when this movement is continued by screwing it down the proper distance. The collar 26 is then secured rigidly upon the shaft by the set-screw 28, a screw-driver (not shown) being inserted diagonally down into the chamber 4 to accomplish this purpose. The bearing-balls 30 are now deposited carefully in the groove 29 of collar 28^a, and the plug 31 is fitted upon the upwardly-projecting end of the shaft and screwed home in the opening 7 until its groove 32 engages the balls 29, said screw-plug therefore obviously forming a journal for one end of the shaft 23. (See Fig. 2.) The base or stand may now be returned to its natural or upright position and the screw 20 screwed down into the worm-gear 12.

The cover-plate 33, preferably of sheet metal and provided with a central opening through which the screw 20 extends, is secured by bolts 34 to the top of the stand or base, so as to cover the chambers 3 and 4 from view, and thus prevent dust or other foreign substance from obtaining access to the operative parts, and said cover-plate is formed with radial indicating-marks 35, wherewith the index-finger 36, secured to the wheel 12, is adapted to register and indicate by its position with relation to any particular indicating-mark the height to which the screw has been elevated.

Upon one end of the shaft 23 a ratchet-wheel 24^a is secured by means of a key 25^a or equivalent means, and journaled upon the hub extensions 26^a of said wheel are the plates 27^a 28^a, the plate 27^a by preference being provided with flanges 27^a' and 29^a, which project laterally and bear against the inner face of plate 28^a, so as to form a rectangular socket, in which the lever 30^a fits snugly but detachably. The plates 27^a and 28^a are secured together by the cross-bolts 31^a, and projecting from plate 27^a are the ears 32^a, to and between which is pivoted an arm 33^a, adapted to be thrown at right angles to the plate 27^a in order that said plate and said arm may constitute a crank-handle, whereby the shaft 23 may be turned more rapidly than by the up-and-down manipulation of lever 30^a, the crank-arm being designed for use with comparatively-light loads, while the lever is for use with heavy loads. In the revolution of the crank it is obvious that its tendency under the pressure applied would be to swing outward in the direction indicated by the arrow beyond its operative position, as shown in Fig. 5; but this difficulty is overcome by providing it with an extension 34^a, which bears against the plate and prevents further movement in the direction indicated. When

the arm is not in use, it is folded back to the inoperative position. (Shown in Fig. 4.)

35^a designates a spring which, as shown at 36^a or otherwise, is secured to plate 28^a and provided at its free end with a conical lug or tooth 37, projecting through an opening 38 in plate 28^a and engaging one of the beveled or inclined surfaces 39 of the stem end of the Y-shaped dog 40, said dog being pivoted between plates 27^a 28^a and having its opposite arms or branches terminating in teeth 41 42, one or the other of said teeth being held in engagement with the ratchet-wheel 24^a by means of the spring-pressed lug or tooth 37, 80 engaging the beveled surface 39 of the dog diagonally opposite to the tooth which engages the wheel. The dog is provided with a handle 43, which is manipulated to overcome the resistance of the spring-pressed lug 85 or tooth 37 and reverse the position of the dog, so that the movement of the lever or crank will cause the shaft to turn in the opposite direction. In raising the lever after each down or power stroke the operative tooth 90 of the dog must of course slip back over one or more teeth of the ratchet, and to accommodate this pivotal action of the dog the spring-pressed lug or tooth 37 must yield, pressure being applied upon the same by the 95 opposing beveled surface 39 of the dog sliding under the lug or tooth; but in this action the point of said lug or tooth never becomes totally disengaged from said beveled surface, because the operative tooth clears the periphery of the ratchet-wheel tooth just about the same time the said lug or tooth reaches the upper edge of said beveled surface, and as the operative tooth of the dog clears the tooth of the ratchet-wheel the spring-pressed lug 105 or tooth by pressure on said beveled surface instantly causes the pivotal oscillation of the dog and snaps its said tooth into the registering notch of the ratchet-wheel. When the opposite tooth of the dog is engaged with the 110 ratchet-wheel, the spring-pressed lug or tooth 37 is in engagement with the beveled surface 39 at the opposite side of the stem of the dog and acts to hold tooth 42 against the ratchet-wheel, as will be readily understood.

115 In the practical operation of this lifting-jack it is sometimes found necessary to lift an object which rests squarely upon the ground and under which the "jack" cannot be conveniently placed. To accommodate this class 120 of objects, I provide the jack with a detachable hanger 44, which bears against the side or the swelling 1^a on the side of the base or stand for the purpose of causing the jack to sustain the weight endwise without any lateral or twisting strain upon the screw. This hanger is provided at its lower end with a foot 45 to underlie the object to be lifted and at its upper end with an arm 46 to rest upon the head of the jack, said arm being formed with 125 opposite hooks 47 to embrace the sides and the under side of the head. The hanger is fitted 130

upon the screw-head in an obvious manner and is formed with a brace-rib under the arm 46. Supposing the parts to be arranged as shown, it is only necessary to manipulate the lever or 5 crank, as the case may be, in the proper direction to rotate the worm-wheel and cause the screw to move upward or downward, the weight upon the screw obviously causing the latter to ascend or descend without any twisting or turning movement, it being clear that the tendency of the screw under the rotary action of the wheel would be to turn if not carrying a load. The fact that the worm-shaft and the worm-wheel are both mounted on ball- 10 bearings reduces the friction on said parts to the minimum, and in practice it is found that an enormous load can be elevated by this jack with but a small expenditure of force on the part of the operator, and a single supply of lubricant, such as castor-oil, keeps this 15 jack in perfect working order for a long period of time.

From the above description it will be apparent that I have produced a lifting-jack 20 which embodies the features enumerated as desirable in the statement of invention, and it is to be understood, of course, that changes in the detail construction, arrangement, form, or proportion of the parts will not be considered a departure from the spirit and scope of 25 the invention.

Having thus described the invention, what I claim as new, and desire to secure by Letters Patent, is—

30 1. In a lifting-jack, a base or stand, a screw therein, a worm-wheel therein engaging the screw, a shaft having a worm-thread engag- 35

ing said wheel, and a ratchet-wheel keyed to said shaft, a lever journaled on said shaft, consisting of a plate 27^a having flanges 27^{a'} and 40 29^a, a plate 28^a bearing against said flanges and provided with an opening 38, between flange 29^a and the ratchet-wheel, a dog 40, pivoted between said plates, a spring 35^a secured to the plate provided with the opening 45 38, and provided with a tooth 37 projecting through said opening and engaging said dog, and a handle 30^a fitting between the plates and flanges 27^{a'} and 29^a, substantially as described. 50

2. In a lifting-jack, a base or stand, a screw therein, a worm-wheel therein engaging the screw, a shaft having a worm-thread engaging said wheel, a ratchet-wheel carried on said shaft, and a lever journaled on said shaft, 55 consisting of the plate 27^a, a plate 28^a secured to the plate 27^a, a dog pivoted between said plates and provided with a pair of teeth, a pawl carried by plate 28^a and engaging said dog to hold one of its teeth or the other in engagement with the ratchet-wheel, lugs 32^a projecting from plate 27^a, and a lever or handle 33^a pivoted to and between said lugs, and provided with an extension 34^a adapted to bear against plate 27^a when the handle extends at about a right angle from said plate 27^a, substantially as and for the purpose set forth. 60 65

In testimony whereof I affix my signature in the presence of two witnesses.

JACK CALDWELL.
